HUMIDIFYING APPARATUS

Charles J. Wurmfeld, New York, N. Y.

Application December 17, 1935, Serial No. 54,830

17 Claims.

(CL 237—78)

This invention relates to humidifying apparatus.

The resultant drying or reduction of the relative humidity of air by the superheating of the moisture available in that air, where radiation from steam-heated apparatus is used for heating, is, of course, a well-known factor, both as to the low effective comfort derived from relatively high temperatures, and the active detriment to the health of persons living under such superheated conditions as are created when heating apparatus of this character is utilized. Generally, research has been directed toward simple, inexpensive manufactured apparatus for increasing the humidity of the atmosphere, operating automatically and without supervision. Humidifying apparatus, resulting from such research prior hereto, is cumbrous, inefficient, requires constant supervision, does not, in fact, attain the desired end, and is expensive to manufacture, and difficult to install.

It is an object of the invention to provide a simple device for cooperation with heat-radiating means utilizing steam as the heating medium, thereby to introduce to the atmosphere during the period that the radiating means is effective, a sufficient quantity of water vapor to assure a desired humidity for the atmosphere, so to avoid the defects otherwise attributable to heating from steam-heated radiators.

Merely to discharge steam directly from the radiator into the air has been found undesirable by reason of a number of factors. Among other things, impurities carried along by the steam, moisture entrained in wet steam, and the noise-producing property of a high velocity steam stream issuing into the atmosphere, all require consideration. By apparatus designed in accordance with the invention, these difficulties are solved since there is effected substantially complete separation of the vapor from any solid or liquid. Only after such separation is the vapor discharged into the atmosphere, it then being in as dry a state as possible under such circumstances. Also, with the solid matter thus removed, the vapor can damage neither the humidifying apparatus, nor furniture in its immediate vicinity.

Apparatus in accordance with the invention is constructed so that any loss of heat by the steam, as it approaches the point where it is discharged into the atmosphere, from which condensate may be formed, will be counteracted, but, in the event any such condensate should be formed, or entrained moisture be involved, either or both will

drain back into the heating means or radiator, and, with such condensate as normally forms in such radiator, will be conducted to the proper return.

Humidifying apparatus in accordance with the invention, by but slight variation in one or more elements of its construction, in accordance with certain definite standards, may be caused to discharge a quantity of vapor proportioned in accordance with the particular heating means with which it is associated, or the quantity of steam necessary for efficient heating and a healthful atmosphere. At the same time, the general construction, and especially at the points of discharge of steam into the atmosphere, is such that undesirable or annoying sound will be produced during the operation of the humidifier.

The apparatus is of simple construction, lending itself to manufacture on a low-priced basis. At the same time, such factors as leakage, drip, and corrosion are minimized, or even completely eliminated.

An object of the invention is to provide apparatus of the character stated, in which the manner in which vapor is fed from the humidifier to the atmosphere is such as to cause, not only elimination of condensate externally of the humidifying apparatus, but even increased circulation of air past the humidifying apparatus. As is well known, the action of jets, and especially of jets of steam, discharged into the atmosphere, tends to cause flow of air in the direction of the jets. By locating the humidifying apparatus with relation to the air currents derived from heating apparatus of the type discussed, so that the jets discharge in the same direction as the normal air-flow past such heating apparatus, increased circulation of air past both heating apparatus and humidifying apparatus will occur.

With such increased flow of air, not only will there be increased and more uniform heating of the air of a chamber within which such heating apparatus is made operative, but, further, if there be any tendency on the part of the discharging steam to carry moisture along with it into the atmosphere, that tendency will be counteracted. The large quantities of warm air, circulating past the humidifying apparatus, will quickly either re-evaporate, or absorb, any such moisture. At the same time, the flow, past the humidifying apparatus, of warm air in increased quantities will tend to maintain a higher external temperature around the humidifying apparatus, so that condensation within the humidifying apparatus will proceed, if at all, at an inappreciable rate.

It is an object of the invention to provide humidifying apparatus for cooperation with heating apparatus using steam as a heating medium, in which the humidifying apparatus is positioned in the currents of air in motion as produced from the action of the heating apparatus, and in which the shaping of the humidifying apparatus is such as to interfere, to a minimum degree, with the flow of air past the heating apparatus. For this purpose, the humidifying apparatus is shaped in substantial conformity with stream-lining principles, so that the flow of vapor from the humidifying apparatus will assist, while the apparatus itself does not interfere with, air-flow around and past the heating apparatus.

Other objects of this invention will hereinafter be set forth, or will be apparent from the description and the drawings, in which are illustrated certain elements considered pertinent for the demonstration of the invention.

The invention, however, is not intended to be restricted to any particular method of operation, construction, or arrangement of parts, or any article of manufacture specifically herein shown and described, or to any particular application of any such article or method, or to any specific manner of use, or to any of various details thereof, herein shown and described, as the same may be modified in various particulars, or 30 be applied in many varied relations, without departing from the spirit and scope of the claimed invention, the elements herein illustrated and described being merely of types to show some of various forms the invention might take for practical purposes.

On the drawings, in which the same reference characters refer to the same parts throughout and in which are shown the elements mentioned:

Fig. 1 is a perspective view of a steam-heated radiator having associated therewith apparatus in accordance with the invention;

Fig. 2 is an elevational view of a humidifier in accordance with the invention, parts being broken away in section to illustrate the internal construction thereof;

Fig. 3 is a cross-sectional view, taken transversely vertically on the line 3—3 through the humidifier shown in Fig. 2;

Fig. 4 is a detail end elevational view of the casing of the humidifier shown in Fig. 2.

Fig. 5 is a perspective view of elements used in the construction of a humidifier and at an intermediate stage of their assembly, in accordance with the construction shown in Figs. 2, 3, and 4, parts being broken away in section to illustrate the method of assembly;

Fig. 6 is a view in perspective, of a humidifier of modified construction, shown broken away in part to illustrate the internal construction thereof;

Fig. 7 is a cross-sectional view, taken transversely vertically, on the line 7—7, through the humidifier shown in Fig. 6; and

Fig. 8 is a view, similar to Fig. 7, of a humidifier of modified construction.

In the construction shown in Figs. 1, 2, 3, 4, and 5, a humidifier 10, embodying certain features of the invention, has been assembled with, and connected to, a steam-heated radiator 12, here shown as being of conventional construction, having an air-venting port 14. Such a radiator may be comprised of a plurality of sections 16, each of which, in turn, may have one or more columns 18 to define openings 20 through the section and between the columns. When assembled, such

openings 20 usually become associated in such manner as to produce substantially continuous passages 22 through the radiator. In addition, the sections may be so shaped and their connection to each other may be so formed that air spaces 24 extending transversely between adjacent sections are produced. This construction effectively provides for the movement of air, heated by the radiator, upwardly away from the heat-radiating surfaces.

In one application of the invention, humidifier 10 is made in such dimensions that it may fit, however snugly, into a through passage 22. Such a humidifier, by means of a duct 26 and a coupling 28 at the end of the duct, is connected into port 14 to which customarily the air-venting valve for such a radiator is connected. The humidifier, for certain purposes of the invention, may be tilted slightly so that its base-line 30 has a downward pitch toward duct 26, which in turn, and with couplings 28, provides a continuously downwardly directed guide for condensate formed in the humidifier, or in the duct leading thereto, to the radiator.

The humidifier of Figs. 1 to 5, inclusive is seen to comprise a casing 32 at the lower end of which enters duct 26, and from the upper portion of which, by means of orifices 34, steam may be discharged into the atmosphere. To make the humidifier effective properly to discharge steam into the atmosphere, without danger of also discharging moisture, which might be precipitated upon flooring in the immediate vicinity of radiator 12, is an important factor in connection with this invention. By the capability of uninterrupted movement of any condensate from casing 32 back through duct 26 and coupling 28, into the radiator, such moisture is normally removed out of relation to orifices 34. By its position within passage 22, casing 32 is directly in the air currents initiated by the hot surfaces of the radiator. Being closely adjacent the walls of the columns, and even in direct contact therewith, by making the width of the casing sufficiently large to permit insertion of the casing into passages 22 with a snug fit, even to the point of exerting slight compression on the walls of the casing, the casing itself will be heated to a high temperature, and will be so maintained. Under these circumstances, there will be no substantial lowering of temperature in the casing to induce condensation, and especially at orifices 34. In fact, there seems to be a drying effect upon the steam derived from this cooperation.

By means of filtering means 36, any moisture discharge from the casing may be prevented. Such filtering means, which may be constructed as hereinafter further described, may also serve to muffle the discharging steam for eliminating undesirable hissing or whistling as the humidifier operates.

Casing 32 may be constructed in any desired manner. A specific form, shown in Figs. 2 to 5, inclusive, is made up with a piece 38 of tubular metal, preferably brass or copper, of oblong cross-section, and with rounded ends, as a foundation, as shown in Fig. 5. The width between walls 40 and 42 of such tubular piece may be just sufficient so that the casing may be positioned within a passage 22 by pushing it thereinto by hand. While the tubing is still open-ended, a thin strip 44 of canvas, upon which has been spread out a layer of absorbent cotton 46, is slipped within bore 48 of the casing while piece 38 is positioned reversely of the disposition shown

by Fig. 5. The canvas, with the cotton on top of it, is pressed down against a wall 50 of a rounded end 52. The canvas is preferably of sufficient coarseness that vapor may pass therethrough. The absorbent cotton may be medicated, thus reducing, to a minimum, the possibilities of the growth of fungi with continued aging of the apparatus.

Once the canvas and cotton have thus been positioned, a metallic strap 54 may be inserted into bore 48, and be pressed down against the cotton, thus firmly holding cotton and canvas in position. Now a section 56 of screening, which may be of coarse mesh, bent into U shape, is to be located within bore 48. The screening is so proportioned that, when so bent, and fitted within bore 48, its legs 58 will extend substantially the entire length of walls 40 and 42, with ends 60 biased out of the normal plane of legs 58 by the rounding of wall 62 of the casing, as shown in Fig. 3. With canvas and cotton retained by strap 54, the bent screening section is slid into bore 48, with legs 58 held substantially together and out of their normal relation. On release of the screening section within bore 48, and removal of strap 54, the canvas and cotton will remain within the bore, and cross-bar 64 of the U, made of sufficient width to fit substantially snugly within bore 48, will ride up against the cotton and canvas, owing to the natural resiliency of the screening, to clamp them between the cross-bar and wall 50.

Screening 56, in length, does not encompass the entire extent of casing 32. Once the screening has been positioned, duct 26, which, preferably, is a tube of a metal such as copper, capable of being worked readily to a desired shaping, is inserted into bore 48. The tube is substantially in diameter the same dimension as the bore. The duct may be inserted into the bore about one inch, in the case of a casing six inches in length. In the same manner, at the other end of the bore, a plug 66, substantially of the same diameter as duct 26, may be inserted for substantially the same distance. Now, with duct and plug inserted in this manner, the entire assembly is positioned in a press having dies so formed that, on operation of the press, the metal will be deformed as shown in Figs. 2 and 4, bringing together edges 68 at the open ends of the casing. The seams, formed by bringing these edges together, and also around duct 26 and plug 66, are closed in any desired manner, such as brazing or soldering. Owing to the pressure to which this construction is subjected, assurance against leakage is requisite.

Duct 26 may be completed by positioning coupling 28 thereon, this coupling being of any desired standard construction. The length of duct 26 is such that, with L nipple 70 inserted and connected into port 14, and with casing 32 positioned in passage 22, the duct may be bent to bring nut 72 into engagement with nipple 70, thus to complete the connection between the humidifier and the radiator.

When the assembly, as described, has been made, or even without the addition of the coupling, the entire construction of duct and casing may be completed. A plurality of orifices 34 are drilled through rounded end 52. Canvas strip 44 need not extend the entire length of the casing, but merely extend sufficiently on either side of orifices 34 to assure that steam should not escape through the orifices unless it first pass through the canvas. Orifices 34 may be about

three-eighths inch apart. With a chisel or similar instrument, a transverse line indentation 74 may be produced in rounded end 52, between pairs of such orifices. In effect, therefore, pairs of walls 76 are thus produced, from which are directed such orifices so that, when steam is supplied under pressure, jets issuing from the orifices, if the orifices are properly aligned, will impinge one upon the other. It has been found desirable that this collision of the jets should take place about one-quarter inch above the casing, and that the indentation be such that the jets issue at about an angle of 60°. It has been found that such relationship of the jets is effective to muffle, to a remarkable degree, the issuing jets, so that, even though the pressure in the radiator be as high as six pounds, substantially no sound of any noticeable character is heard. The number of pairs of orifices and the size of the drillings for such orifices may be varied in accordance with the amount of steam to be emitted for a proper adjustment of the humidity factor.

At this last operation, the humidifier, after attaching the coupling, is in condition for use. As will be noted, duct 26 discharges steam into unobstructed bore 48 of the casing, which, in turn, is heated by the hot air of radiator 12, as well as, in part at least, by direct contact with the radiator walls. The steam passes through filtering means 36, to issue as jets from orifices 34. As these jets are directed upwardly from the humidifier, and in the general direction of flow of air currents normally produced by the radiator, it naturally follows that these jets, rather than counteracting normal circulation, will induce and increase such circulation. In addition to this, the rounding of walls 50 and 62 serve to stream-line the unit, thereby to eliminate interference by the humidifier with the normal air circulation about the radiator.

In Figs. 6 and 7, there is shown a humidifier 78, constructed in a somewhat modified manner. Such humidifier may be formed from a piece of sheet metal bent to form a U-shaped container 80. A duct 82, similar to duct 26, having a coupling similar to coupling 28, and a plug similar to plug 66, are assembled against wall 84, forming the cross-bar of the U. Duct 82, in this case, may extend the entire length of wall 84, having orifices 86 formed therethrough at intervals. In such case, the extreme end of the duct may be plugged.

A covering of absorbent cotton 88 may be positioned over the tube to cover the orifices. To clamp the covering in position, a U-shaped screen 90 is formed, the legs of the U being slightly higher than the depth of covering and duct with which it is to cooperate. This screen is slipped down through container 80, so that the legs are positioned immediately over the covering, and then the screen is pushed beyond the covering so that the legs clinch around duct 82, as shown in Fig. 7. By a proper tool, screen 90 may be driven firmly down into this position. End edges 92 of container 80 are closed around duct 82, substantially in the same manner as described for casing 32, or by a bent-metal joint. However, walls 94 are left open at the top end.

Steam, entering container 80 from duct 82, is discharged through orifices 86, through cotton covering 88, and then passes up between walls 94, to join with the air currents moving past the radiator. In this case, also, the upward flow of hot vapor, together with its directional effect,

enhances the circulation of the air past the radiator. At the same time, walls 94, heated from the rising hot air, serve to counteract the formation of condensate, heating or superheating the vapor and any moisture entrained therein. The covering serves to muffle any sounds otherwise derivable from the jets.

In Fig. 8, is shown a humidifier 96, such as appears in my co-pending application, Serial No. 597,854, filed March 9th, 1932. In this case, the construction is similar to that described for container 80, except either that orifices 86 need not be used, or that covering 88 is actually a filling for the space between walls 94, with screen 90, as shown in Fig. 8, retaining the filling, and bridging over the mouth 98 of the humidifier.

As shown in Fig. 6, duct 82, which may be formed and arranged similarly for either of the constructions of Figs. 6 or 8, like duct 26, extends outwardly beyond container 80, and then downwardly, to provide means for retention of a reducing nipple 100, associated with an L 102, which, in turn, is retained by a coupling 104 carried at the end of duct 82. Nipple 100 includes a wall 106, having a small orifice 108 therethrough, for controlling flow of steam to the humidifier. The reducing L is screwed into an opening in the radiator wall, and the humidifier is fixed in position by engaging the L by coupling 104 at the end of duct 82. In this manner, the entrance to duct 82 is governed by orifice 108. It has been found that, to effect the purposes of the invention, it is desirable that the passage area of orifice 108, then nipple 100, and finally conduit 82, increase by gradual stages, but, finally, the passage area of conduit 82 is less than the effective areas of orifices 86, while the extent of opening across the mouth of container 80 is greater than the area of orifices 86.

Many other changes could be effected in the particular elements designed, and in the methods of manufacture and use, and in the apparatus therefor, and in the article manufactured, herein set forth, and in specific details thereof, without substantially departing from the invention intended to be defined in the claims, the description being merely of elements illustrating certain phases of the spirit of the invention.

What is claimed as new and useful is:

1. Apparatus for producing a substantially uniform discharge of water vapor into the atmosphere to increase its humidity without condensation of the vapor, the apparatus including a casing, the casing being provided with means for venting water vapor upwardly into the atmosphere away from the casing, the casing being tubular, the tube being defined by a pair of vertically extending substantially parallel walls and end walls extending between the parallel walls, the distance between the parallel walls being less than the height of a parallel wall, the venting means being positioned in the upper portion of the casing, the bottom end wall being shaped to facilitate air-flow upwardly past the casing, and a conduit having an end inserted a short distance into the bore of the casing, the end resting upon the bottom end wall, the parallel walls being pressed around the conduit end to seal the casing at that end.
2. Apparatus for producing a substantially uniform discharge of water vapor into the atmosphere to increase its humidity without condensation of the vapor, the apparatus including a casing, the casing being provided with means for venting water vapor upwardly into the atmos-

sphere away from the casing, the casing being tubular, the tube being defined by a pair of vertically extending substantially parallel walls and end walls extending between the parallel walls, the distance between the parallel walls being less than the height of a parallel wall, the venting means being positioned in the upper portion of the casing, both end walls being shaped to facilitate air-flow upwardly past the casing, and a conduit having an end inserted a short distance into the bore of the casing, the end resting upon the bottom end wall, the body of the casing extending away from the conduit end, the parallel walls being pressed around the conduit end to seal the casing at that end.

3. Apparatus for producing a substantially uniform discharge of water vapor into the atmosphere to increase its humidity without condensation of the vapor, the apparatus including a casing, the casing being tubular, the tube being defined by a pair of vertically extending substantially parallel walls and end walls extending between the parallel walls, the distance between the parallel walls being less than the height of a parallel wall, the bottom and top end walls being convexed to facilitate air-flow upwardly past the casing, a conduit having an end inserted a short distance into the bore of the casing, the end resting upon the bottom end wall, the body of the casing extending away from the conduit end, the parallel walls being pressed around the conduit end to seal the casing at that end, the top end wall being indented transversely of its convexity to form sloping walls intermediately of the convexity, and orifices opening through the sloping walls and communicating with the bore of the casing.

4. Apparatus for producing a substantially uniform discharge of water vapor into the atmosphere to increase its humidity without condensation of the vapor, the apparatus including a casing, the casing being tubular, the tube being defined by a pair of vertically extending substantially parallel walls and end walls extending between the parallel walls, the distance between the parallel walls being less than the height of a parallel wall, both end walls being convexed to facilitate air-flow upwardly past the casing, a conduit having an end entering the bore of the casing immediately at the bottom end wall, the top end wall having a pair of sloping faces, and orifices opening through the sloping faces and communicating with the bore of the casing, the formation of the orifices in the faces being such that jets of vapor issuing from opposed faces will impinge one upon the other.

5. Apparatus for producing a substantially uniform discharge of water vapor into the atmosphere to increase its humidity without condensation of the vapor, the apparatus including a casing, the casing being tubular, the tube being defined by a pair of vertically extending substantially parallel walls and end walls extending between the parallel walls, the distance between the parallel walls being less than the height of a parallel wall, both end walls being convexed to facilitate air-flow upwardly past the casing, a conduit having an end entering the bore of the casing immediately at the bottom end wall, the top end wall having orifices formed therethrough and communicating with the bore of the casing, the formation of the orifices being such that jets of vapor issuing from the orifices will be directed toward each other and will impinge one upon the other.

6. Apparatus for producing a substantially uniform discharge of water vapor into the atmosphere to increase its humidity without condensation of the vapor, the apparatus including a casing, the casing being tubular, the tube being defined by a pair of vertically extending substantially parallel walls and end walls extending between the parallel walls, the distance between the parallel walls being less than the height of a parallel wall, both end walls being convexed to facilitate air-flow upwardly past the casing, a conduit having an end entering the bore of the casing immediately at the bottom end wall, the top end wall having orifices formed therethrough and communicating with the bore of the casing, the formation of the orifices being such that jets of vapor issuing from the orifices will be directed toward each other and will impinge one upon the other, and gas-filtering means positioned in the casing bore at the orifices.

7. Apparatus for producing a substantially uniform discharge of water vapor into the atmosphere to increase its humidity without condensation of the vapor, the apparatus including a casing having an inlet at the lower portion thereof, the casing being tubular and being less in width than in height, the tube of the casing including bottom and top walls, both bottom and top walls being convexed to facilitate air-flow upwardly past the casing, the top wall of the casing having orifices formed therethrough and communicating with the bore of the casing, the formation of the orifices being such that jets of vapor issuing from the orifices will be directed toward each other and will impinge one upon the other, gas-filtering means positioned in the casing bore at the orifices, and a screen in the casing bore for retaining the gas-filtering means in position.

8. Apparatus for producing a substantially uniform discharge of water vapor into the atmosphere to increase its humidity without condensation of the vapor, the apparatus including a casing having an inlet at the lower portion thereof, the casing being tubular and being elongate vertically of its transverse cross-section, the casing having outwardly convexed top and bottom walls to facilitate air-flow upwardly past the casing, the top wall having orifices formed therethrough and communicating with the bore of the casing, the formation of the orifices in the wall being such that jets of vapor issuing from the orifices will be directed toward each other and will impinge one upon the other, gas-filtering means positioned in the casing bore at the orifices, and a screen of U-shaped transverse cross-section in the casing bore for retaining the gas-filtering means in position, the screen being positioned in the casing so that its U is inverted with the bottom of the U in engagement with the gas-filtering means.

9. Apparatus for producing a substantially uniform discharge of water vapor into the atmosphere to increase its humidity without condensation of the vapor, the apparatus including a casing having an inlet at the lower portion thereof, the casing being tubular and being elongate vertically of its transverse cross-section, the casing having outwardly convexed top and bottom walls to facilitate air-flow upwardly past the casing, the top wall having orifices formed therethrough and communicating with the bore of the casing, the formation of the orifices in the wall being such that jets of vapor issuing from the orifices will be directed toward each other and

will impinge one upon the other, gas-filtering means positioned in the casing bore at the orifices, and a screen of U-shaped transverse cross-section in the casing bore for retaining the gas-filtering means in position, the screen being positioned in the casing so that its U is inverted with the bottom of the U in engagement with the gas-filtering means, the arms of the U extending downwardly and being compressed and urged upwardly by engagement against the bottom wall.

10. A humidifying attachment for a steam source, the attachment including a diffusing body, an inlet to the body, and a conduit connected to the inlet, the diffusing body including a casing forming a chamber and being greater in length than height, the inlet opening into the chamber at the lower elongated portion thereof, the casing having an outlet from the chamber at the upper portion thereof, a packing within the chamber between the outlet and the communication of the inlet with the chamber, and a screen for retaining the packing in position, the passage area of the conduit being less and the passage area of the outlet being greater than the effective passage area at the opening of the inlet into the chamber.

11. A humidifying attachment for a steam source, the attachment including a diffusing body, and an inlet to the body, the diffusing body including a casing forming a chamber, the inlet including a duct extending along the bottom of the chamber, the duct having a plurality of openings in the chamber, the casing having an outlet from the chamber at the upper portion thereof, a packing within the chamber between the outlet and the openings, and a screen for retaining the packing in position, the passage area of the duct being less and the passage area of the outlet being greater than the effective passage area of the openings.

12. In combination with a steam-heating radiator having an air passage extending through the body thereof; an humidifier for discharging steam from the radiator; and means for connecting the humidifier to the radiator, the connecting means comprising a substantially continuously upwardly directed conduit for receiving steam from the radiator and conducting it to the humidifier, the passage through the conduit being clear of stopping means; the humidifier, the conduit, and the radiator being so related that condensate will tend to flow reversely of the steam flow and back to the radiator; the humidifier comprising an elongate casing; the cross-section of the casing transversely of its length being such that the humidifier may fit substantially closely within the passage; the conduit discharging into the casing; the casing providing means for maintaining in vaporized condition steam discharged thereinto, and for so directing the steam outwardly into the passage as to assist the movement of air currents induced by the radiator.

13. In combination with a steam-heating radiator having an air passage extending through the body thereof, an humidifier for discharging steam from the radiator; and means for connecting the humidifier to the radiator, the connecting means comprising a conduit for receiving steam from the radiator and conducting it to the humidifier, the passage through the conduit being clear of stopping means; the humidifier, the conduit, and the radiator being so related that condensate will tend to flow reversely of the steam flow and back to the radiator; the humidifier comprising an elongate casing; the cross-section of the casing

transversely of its length being such that the humidifier may fit substantially closely within the passage; the conduit extending into and along the bottom of the casing, and being in open communication with the casing within the casing; the casing providing means for maintaining in vaporous condition steam discharged thereto, and for so directing the steam outwardly into the passage as to assist the movement of air currents induced by the radiator.

14. In combination with a steam-heating radiator having an air passage extending through the body thereof; an humidifier for discharging steam from the radiator; and means for connecting the humidifier to the radiator, the connecting means comprising a conduit for receiving steam from the radiator and conducting it to the humidifier, the passage through the conduit being clear of stopping means; the humidifier, the conduit, and the radiator being so related that condensate will tend to flow reversely of the steam flow and back to the radiator; the humidifier comprising an elongate casing; the casing being substantially an elongated U in cross-section transversely of its length so that the humidifier may fit substantially closely within the passage; the conduit extending into the casing and fitting snugly in the bottom of the U; the conduit having openings directed into the casing; the casing comprising means for maintaining in vaporous condition steam discharged thereto, and for so directing the steam outwardly into the passage to assist the movement of air currents induced by the radiator; the casing having means therewithin and above the conduit for muffing the discharge of steam from the openings.

15. The combination of a steam heated radiator made up of a plurality of conventional multi-column sections; a humidifier for discharging steam from the radiator; conduit means for connecting the humidifier to the radiator; the conduit means and humidifier being so constructed and arranged relative to the radiator that condensate formed in said humidifier will tend to gravitate to the radiator; the humidifier comprising an elongated casing positioned longitudinally of the space formed longitudinally of the radiator by the columns of the sections of the radiator, the dimensions of the casing transversely of its length being such that the humidifier fits closely within said space, the casing being provided with discharge apertures throughout its length so directed that the discharged steam assists the upward flow of air currents over the

radiator, the humidifier also comprising means for maintaining in vaporous condition the steam discharged thereto.

16. The combination with a steam-heated radiator; a humidifier for discharging steam from the radiator; conduit means for connecting the humidifier to the radiator; the humidifier and the conduit means being so constructed and arranged relative to the radiator that condensate formed in said humidifier will tend to gravitate to the radiator; the humidifier comprising an elongated casing; the casing, when the humidifier is in position, being disposed substantially horizontally and immersed directly in the air-stream induced by the radiator; the casing being disposed with its side walls extending in substantially the same general direction as the direction of the air-stream; the casing having an opening in the direction of the movement of the air-stream past the casing so that the steam discharged from the casing will assist the upward flow of air currents over the radiator and the casing will interfere to a minimum degree with the movement of the air currents, the humidifier also comprising means for maintaining in vaporous condition the steam discharged thereto.

17. The combination with a steam-heated radiator; a humidifier for discharging steam from the radiator; conduit means for connecting the humidifier to the radiator; the humidifier and the conduit means being so constructed and arranged relative to the radiator that condensate formed in said humidifier will tend to gravitate to the radiator; the humidifier comprising an elongated casing; the casing, when the humidifier is in position, being disposed substantially horizontally and immersed directly in the air-stream induced by the radiator; the casing being disposed with its side walls extending in substantially the same general direction as the direction of the air-stream; the bottom of the casing being substantially convexedly rounded; the casing having an opening in the direction of the movement of the air-stream past the casing so that steam discharged from the casing will assist the upward flow of air currents over the radiator and the casing will interfere to a minimum degree with the movement of the air currents, the humidifier also comprising means for maintaining in vaporous condition the steam discharged thereto.

CHARLES J. WURMFELD.
